UNITED STATES PATENT OFFICE.

FRANK CARMINE TEDESCO, OF DICKSON CITY, PENNSYLVANIA.

FOLDING FLOWER-STAND.

No. 923,089.

Specification of Letters Patent.

Patented May 25, 1909.

Application filed January 27, 1909. Serial No. 474,447.

To all whom it may concern:

Be it known that I, FRANK CARMINE TEDESCO, a citizen of the United States, residing at Dickson City, in the county of Lackawanna and State of Pennsylvania, have invented certain new and useful Improvements in Folding Flower-Stands; and I do declare the following to be a full, clear, and exact description of the invention, such as will enable others skilled in the art to which it appertains to make and use the same.

This invention relates to improvements in folding flower stands for windows.

The object of the invention is to provide a folding flower stand adapted to be applied to a window and having means whereby the same may be readily secured to the window frame.

A further object is to provide a flower stand of this character which may be readily folded to a small compact form, and means whereby the same is held in an open or folded position.

With these and other objects in view, the invention consists of certain novel features of construction, combination and arrangement of parts, as will be more fully described and particularly pointed out in the appended claims.

In the accompanying drawing, Figure 1 is a perspective view of the stand showing the same applied to a window; Fig. 2 is a vertical longitudinal sectional view; Fig. 3 is a vertical transverse sectional view; Fig. 4 is a horizontal section taken above the lower shelf; Fig. 5 is a detail horizontal section, showing the means whereby the stand is secured to the window frame; and Fig. 6 is a side view of the stand in folded position.

Referring more particularly to the drawings, 1 denotes a stand which comprises a series of vertical corner posts or standards 2, each of which is provided in its inner side with a longitudinally disposed groove or channel 3. The corner posts or standards 2 are connected together by a series of shelf-supporting bars 4 on which are arranged a series of shelves 5. In the present instance I have shown three shelves arranged on the supports 4. The lowermost shelf is hingedly connected to one of the lower cross bars 4 and is adapted to be folded upwardly into engagement with the corner posts when the stand is in a folded position. In the opposite end of the lower shelf is formed a locking notch 6, said notch being engaged with a

bolt 7 arranged in the lower cross bar 4 of the corner posts at one end of the stand, whereby said end may be adjusted to vary the width of the stand. The bolt 7 is provided with a clamping nut 8 whereby when the end of the stand has been adjusted to fit the window, said end may be securely clamped to the bottom shelf.

The intermediate and upper shelves of the stand have pivotally connected to each side and adjacent to one end guide blocks 9, said blocks being adapted to slidably engage the grooves or channels formed in the inner sides of the corner posts 2. By thus connecting the end of the shelf with the corner post, said end may be slipped up and down between the corner post to permit the opposite end to be disengaged from its cross bar or support at the opposite end of the stand, after which the shelf may be folded or swung downwardly along side the ends of the stand, thus permitting said ends to be closed together and the stand brought to a folded position.

In order to hold the stand in its open or closed position, I provide a pair of diagonally arranged crossed brace bars 10, said bars being pivotally connected together midway their ends and having their lower ends pivotally connected to the opposite lower corners of the outer side of the stand, as clearly shown in Fig. 1 of the drawing. The upper portions of the brace bars 10 are provided with longitudinally disposed slots 12 and said slotted portions are engaged with guide bolts 13 arranged in the opposite upper corners of the stand. On the bolts 13 are clamping nuts 14 which are adapted to be screwed up into engagement with the upper ends of the brace bars, thereby firmly clamping the same against the upper ends of the outer supporting standards 2, and thus rigidly holding the stand in an open or folded position. In addition to the brace bars 10, I also provide an attaching bar 15 which is pivotally connected at one end of one of the inner corner posts or standards 2, and in its opposite ends has formed a series of notches 16, one of which is adapted to be engaged with a clamping bolt and nut 17 whereby the attaching bar may be secured to the stand when adjusted to different widths, and will serve also to assist in bracing and holding the stand in its open position. In the attaching bar adjacent to its opposite ends are formed longitudinally disposed slots 18 in which are

arranged fastening bolts 19 having hook shape inner ends 20 adapted to be engaged with the stop strips or guides of the window frame when the stand is arranged in position 5 on the outer side thereof. The inner ends of the bolts 19 are threaded and on said threaded ends are screwed clamping nuts 21, whereby the hook ends of the bolts may be drawn into firm engagement on the stop strips, thus securely fastening the frame in position against the window.

When the stand is not in use the same may be folded into a small compact form as shown in Fig. 6 of the drawing. In folding 15 the stand the clamping nuts 14 are released and the shelves are disengaged at one end from their supporting bars then swung downwardly or upwardly against the supporting standards forming the ends of the stand, 20 after which the attaching bar is disengaged from the clamping bolt connection 17 and swung downwardly which will permit the opposite ends of the stand to be pushed together as shown. After the ends have been 25 thus pushed together the clamping nuts 14 may be again tightened up on the guide bolts 13, thus clamping the ends of the stand in closed or folded position.

From the foregoing description, taken in 30 connection with the accompanying drawings, the construction and operation of the invention will be readily understood without requiring a more extended explanation.

Various changes in the form, proportion 35 and the minor details of construction may be resorted to without departing from the principle or sacrificing any of the advantages of this invention as defined in the appended claims.

40 Having thus described and ascertained the nature of my invention, what I claim as new and desire to secure by Letters-Patent, is:—

1. A folding flower stand comprising corner posts or standards, a series of supports 45 secured to said posts, shelves arranged on said supports and adapted to be folded to permit the stands to be closed, means whereby the stand may be adjusted to fit windows of different widths, and means to secure the 50 parts in their adjusted positions.

2. A folding flower stand comprising a plurality of supporting standards, a series of shelf supports secured to said standards, a series of shelves arranged on said supports, a 55 pair of brace bars pivotally connected at

their lower end to the opposite lower corners of the stand and slidably engaged at their upper ends with the opposite upper corners thereof, and means to adjustably secure said upper corners of the stand to said upper ends 60 of the brace bars.

3. A folding flower stand comprising a plurality of standards, a series of shelf supports secured to said standards, shelves arranged on said supports and adapted to be 65 swung to a folded position, crossed brace bars pivotally connected together at the opposite lower corners of the stand, said brace bars having slotted upper portions, and a clamping bolt and nut connection between the upper ends of said bars and the upper corners of the stand, whereby the latter may be secured in adjusted position to fit windows of 70 various widths.

4. A folding flower stand having a plurality of standards, a series of shelf supports secured to said standards, shelves arranged on said supports and adapted to be swung to a folded position, one of said shelves having a hinged connection at one end, and an adjustable connection at its opposite end to the opposite end of the stand, whereby the latter may be adjusted and secured in its adjusted 80 position, an attaching bar and means whereby said bar is secured to the window frame 85 to hold the stand in operative position.

5. A folding flower stand comprising a plurality of standards, a series of shelf supports secured to said standards, shelves arranged on said supports and adapted to be 90 swung to a folded position, means to hold said stand in an open or closed position, an attaching bar pivotally connected at one end to one end of the stand, and having an adjustable connection with the opposite end of the 95 stand, attaching bolts adjustably engaged with said attaching bar, said bolts having on their inner ends window frame engaging hooks and clamping nuts adapted to be screwed on the opposite ends of said bolts, whereby said 100 hook ends are drawn into firm engagement with the window frame to support the stand in operative engagement therewith.

In testimony whereof I have hereunto set my hand in presence of two subscribing witnesses.

FRANK CARMINE TEDESCO.
